UNITED STATES PATENT OFFICE.

FREDERICK C. BARGAR, OF COLUMBUS, OHIO, ASSIGNOR TO THE NU-EX FIRE APPLIANCE COMPANY, OF COLUMBUS, OHIO, A CORPORATION OF OHIO.

DESIGN FOR A FIRE-EXTINGUISHER CASING.

56,906.

Specification for Design.

Patented Jan. 18, 1921.

Application filed January 22, 1917. Serial No. 143,872. Term of patent 14 years.

To all whom it may concern:

Be it known that I, FREDERICK C. BARGAR, a citizen of the United States, residing at Columbus, in the county of Franklin and State of Ohio, have invented a new, original, and ornamental Design for Fire-Extinguisher Casings, of which the following is a specification, reference being had to the accompanying drawing, forming part thereof.

Figure 1 is a side elevation of my newly designed fire extinguisher, and,

Fig. 2 is a plan view of Fig. 1.

I claim:

The ornamental design for a fire extinguisher casing, as shown.

F. C. BARGAR.
